UNITED STATES PATENT OFFICE.

WILLIAM JOSEPH STILL, OF WEST EALING, ENGLAND.

TUBULAR HEAT-INTERCHANGING APPARATUS.

1,171,900.

Specification of Letters Patent. Patented Feb. 15, 1916.

Application filed April 4, 1914. Serial No. 829,458.

To all whom it may concern:

Be it known that I, WILLIAM JOSEPH STILL, a subject of the King of Great Britain and Ireland, residing at West Ealing, 5 in the county of Middlesex, England, have invented Improvements in or Relating to Tubular Heat-Interchanging Apparatus, of which the following is a specification.

This invention relates to heat interchanging apparatus wherein gilled or other tubes are connected to headers and it has for its object to so arrange the apparatus that headers can be used to build up apparatus involving a large number of tubes with the advantage of being able to remove a few of the tubes with a companion header as a unit without affecting the remainder. Thus, by connecting say three tubes to a header having a lateral opening or branch, a number 15 of the said headers can be connected by the lateral openings or branches to the lower drum or part of a steam generator, the ends of the tubes opposite to the header being connected to an upper drum or part of the 20 generator. In a case of this kind, gills or flanges can be secured to the tubes simultaneously with connection of the tubes to the headers by hydraulic pressure. The headers may be connected to the lower drum 25 or part of the generator by horizontal tubes expanded in place by a tool passed through a hole in each header that is afterward closed by a screw plug. The lower drum may be connected to the upper drum by another set of tubes.

The accompanying drawings illustrate two steam generator constructions according to the invention, Figure 1 being a part sectional elevation and Fig. 2 a part sectional underside view, the section being taken on the line A A of Fig. 1, of one form 40 suitable for use as a launch boiler and Fig. 3 being a part sectional elevation and Fig. 4 a part sectional plan on the line B B of Fig. 3 showing another form of steam generator also suitable for use as a launch boiler.

As shown in Figs. 1 and 2, gilled tubes *a* are connected, in sets of three, to a header *b* having a lateral opening at *c* by which it 45 can be connected to an annular water trunk *d* by a tube *e* expanded in any suitable way

in the header and trunk, as by introduction of a tool through a normally plugged opening at *f*. The upper ends of the tubes *a* 55 extend through a tube plate or wall *g* of a steam and water drum or receiver *h* and each tube may be expanded into contact with the header *b*, the gills *i* and the plate *g* simultaneously by hydraulic pressure as 60 for example by the method and apparatus described in the specification of British Patent No. 23176 of 1912, granted to me and another. The trunk *d* and drum *h* are shown as connected by an annular series of 65 plain tubes *j* arranged nearer the center of the steam generator than the gilled tubes *a* the tubes *j* and trunk forming a downward extension of a water receiver of which the drum *h* forms the upper part. This steam 70 generator is adapted to be heated by flame as from a burner at *m* arranged below the central space *n* surrounded by the tubes *a* and *j*. It may however be otherwise heated as by hot products of combustion led into 75 such central space from any other source.

In Figs. 3 and 4, the steam generator is modified by expanding the tubes *e* of the several headers into a cylindrical down-comer *k* common to them and forming a 80 downward extension or part of the upper steam and water drum or receiver *h*, the arrangement in other respects being similar to that of Figs. 1 and 2 except that the three gilled tubes *a* associated with each 85 header *b* are combined with two plain tubes *o*. This steam generator is specially adapted to be heated by hot gases, such as hot products of combustion, coming from any available source and entering the annular space 90 *n* of the generator through the lateral passage *p*, the water circulating in the direction of the arrows.

In each construction *r* is the casing of the boiler and *s* the uptake for products of combustion, the sets of tubes *a* and headers *b* being arranged in an annular manner in the space between the upper and lower connected portion of the water receiver to which the tubes and headers are respectively connected and the casing of the boiler.

By constructing steam generators in the manner hereinbefore described, water can circulate freely through the tubes and the

upper and lower portions of the steam and water receivers and steam generated in the tubes *a* or *a* and *o* can freely rise through the water in these tubes and pass easily and without obstruction direct into the upper steam and water vessel so as to avoid any possibility of its depressing the water in the tubes and thus permitting of the tubes being overheated and damaged as results with many constructions of tubular steam generators heretofore proposed comprising upper and lower water chambers, vertical water tubes and connections between these parts.

What I claim is:—

1. Heat interchanging apparatus comprising a water receiver having an enlarged upper drum-like portion adapted to serve as a water and steam drum and a downwardly extending portion of smaller cross section than the upper portion and through which water can freely flow in a vertical direction, tubes connected directly to the bottom of the enlarged upper portion of the receiver and extending downwardly toward and terminating near to the bottom of the downwardly extending portion of the receiver, headers connecting such tubes at their opposite and lower ends in sets and tubes connecting said headers to the downwardly extending portion of the receiver near to the bottom thereof.

2. Heat interchanging apparatus comprising a water receiver having an enlarged upper drum-like portion, adapted to serve as a water and steam drum and a downwardly extending portion of smaller cross section than the upper portion and through which water can freely flow in a vertical direction, straight vertically arranged tubes connected directly to the bottom of the enlarged upper portion of the receiver and extending downwardly toward and terminating around and near to the bottom of the downwardly extending portion of the receiver, headers connecting such tubes at their opposite and lower ends in sets and straight horizontal tubes connecting said header to the downwardly extending portion of the receiver near to the bottom thereof.

3. Heat interchanging apparatus comprising a receiver in the form of an upper steam and water drum having a central downcomer of smaller diameter, tubes surrounding the said downcomer and extending through and connected directly to the bottom of the upper drum, headers connecting such tubes at the lower ends in sets and a tube connecting each header laterally to the lower end portion of the downcomer.

4. Heat interchanging apparatus comprising a receiver in the form of an upper steam and water drum having a central downcomer of smaller diameter, a series of externally gilled tubes arranged around said

downcomer, a series of plain tubes disposed between the gilled tubes and the downcomer, all of said tubes extending through and connected directly to the bottom of the upper drum, headers connecting a number of gilled and of plain tubes in sets and a tube connecting each header laterally to the lower end portion of the downcomer.

5. In heat interchanging apparatus embodying a receiver and a number of tubes arranged to be connected direct to such receiver at different levels, a series of headers each having a series of openings in its upper wall adapted to receive some of the tubes and in each of its opposed vertical walls a horizontal opening, one such opening being adapted to receive a tube for connecting the header to the lower end portion of the receiver and the other opening being provided with a removable plug adapted to permit the entry of a tool for expanding the single tube aforesaid into the header and receiver.

6. Heat interchanging apparatus comprising a receiver consisting of an upper portion constituting a steam and water drum and a lower portion of smaller cross section than the upper portion, constituting a water downcomer, a casing around the said lower portion of the receiver, an annular series of headers arranged around but at a distance from the lower portion of said downcomer, sets of vertical tubes arranged between said extension and casing, each set being secured directly to the bottom of said drum and connecting said drum to one of said headers, tubes each connecting a header laterally to the lower portion of the downcomer and extending across the lower end of the space between the sets of tubes and downcomer, a support for said receiver, headers and casing, said support having an inlet passage for hot gases communicating with the bottom of said space and an exit flue for spent gases.

7. Heat interchanging apparatus comprising a receiver consisting of an upper portion constituting a steam and water drum and a lower portion of smaller cross section than the upper portion, constituting a water downcomer, a casing around the said lower portion of the receiver, an annular series of headers arranged around but at a distance from the lower portion of said downcomer and from said casing, vertical sets of plain and gilled tubes connected directly to the bottom of the steam and water drum and arranged annularly between said downcomer and casing so as to form an inner annular space between them and the downcomer and an outer space between them and the casing, the gilled tubes being arranged farthest from the downcomer, and the inner space being closed at the top and the outer space being in communication with

a flue or chimney, tubes each connecting a header laterally to the lower portion of the downcomer and extending across the lower end of the inner space between the tubes and 5 downcomer, a support for said receiver, headers and casing having an inlet passage for hot gases to the inner space and arranged to close the lower end of the outer

space and an uptake flue in communication with the outer space.

Signed at London England this 23d day of March 1914.

WILLIAM JOSEPH STILL.
